ATTORNEY

UNITED STATES PATENT OFFICE.

JOHN CHANI, OF CANAL DOVER, OHIO.

BOTTLE-OPENING DEVICE.

1,108,699.

Specification of Letters Patent. Patented Aug. 25, 1914.

Application filed May 15, 1913. Serial No. 767,930.

To all whom it may concern:

Be it known that I, JOHN CHANI, a subject of the King of Hungary, residing at Canal Dover, in the county of Tuscarawas and State of Ohio, have invented certain new and useful Improvements in Bottle-Opening Devices, of which the following is a specification, reference being had therein to the accompanying drawing.

10 This invention relates to a bottle opening device, and the primary object of my invention is to provide a simple and inexpensive device that can be easily placed in engagement with a bottle or other receptacle for quickly removing a cork, cap or other closure.

20 A further object of this invention is to provide a strong and durable bottle opening device embodying fulcrumed levers, one of which serves as a puller and the other is provided with a cork screw, whereby a cork can be removed from the neck of a bottle.

25 With the above and other objects in view the invention resides in the novel construction, combination and arrangement of parts to be hereinafter specifically described and then claimed.

30 Reference will now be had to the drawing, wherein:

Figure 1 is a side elevation of the device partly broken away and partly in section, and Fig. 2 is a plan of the same.

35 A device in accordance with this invention comprises a bar 1, having one end thereof provided with a yoke 2 adapted to embrace a bottle neck 3. The opposite end of the bar is provided with a depending prong 4 adapted to engage in a bottle cap 5.

40 The bar 1, adjacent to the ends thereof, is provided with detachable uprights 6, and

pivotedly connected to the upper ends of said uprights are fulcrumed levers 7 and 8. The levers 7 and 8 are connected by coiled springs 9 to the uprights 6 and said 45 springs hold the levers 7 and 8 normally in a horizontal plane or normally in parallelism with the bar 1.

The outer end of the lever 7 is provided with a rotatable cork-screw 10 whereby a 50 cork 11 can be removed from the bottle neck 3. The outer end of the lever 8 is bent downwardly and provided with a hook, the outer end of said lever constituting a puller 12 for engaging under the cap 5 and 55 tilting said cap relatively to the bottle, whereby the cap can be easily removed.

Either one of the levers 7 or 8 is operated at the inner end thereof and said operation can be easily accomplished by 60 gripping the bar 1 and pressing the inner end of one of the levers toward said bar.

What I claim is:

A bottle opening device comprising a bar 65 formed at one end with a depending prong adapted for engagement with the bottle cap, an upright 70 detachably mounted on said bar; a lever pivotally mounted on said upright, the outer end of said lever being formed with a downwardly extending portion 75 having a hook formed on the end thereof and adapted for engagement under the edge of a bottle cap, and a spring connected to the said upright for holding said lever normally parallel to said bar.

In testimony whereof I affix my signature in the presence of two witnesses.

JOHN CHANI.

Witnesses:
